BY
Frank W. Ashley
ATTORNEY

UNITED STATES PATENT OFFICE.

ALBERT E. GRANT, OF NEW YORK, N. Y.

GEAR PUMP.

Application filed August 8, 1927. Serial No. 211,325.

My invention relates to gear pumps.

The object of my invention is to provide a gear pump for pumping oil, that may be regulated to deliver more or less oil uniformly without changing the speed of motor to which it is directly attached.

A further object is to provide means whereby one of the gear wheels of the pump may be adjusted relative to the cooperative wheel, 10 from the exterior of the pump while the pump is running.

A further object is to provide an oil tight casing that will prevent leakage.

Further objects and advantages of the construction will be described, and the novel features defined in the claims.

Referring to the drawings which form a part of this specification:—

Fig. 1 is an end view of an electric motor 20 with a pump embodying my invention mounted thereon and shown in vertical section.

Fig. 2 is a side view of the pump showing the casing wall broken away to disclose the 25 pump gears meshed together, and the means for supporting the motor shaft in the pump casing.

Fig. 3 is a sectional plan view of a portion 30 of the pump casing taken on the line 3—3 of Fig. 1.

A, indicates an electric motor provided with an end cap portion A¹ having a bearing A² for the motor shaft B.

The cap A¹ is provided with a smooth 35 plane surface A³. A casing ring C, is formed with parallel sides each having a smooth plane surface C¹—C¹ respectively, (see Fig. 3). The casing ring C is provided with a circular bore D in which is fitted a 40 gear pump element E, the outer periphery of which contacts with the wall of the bore D. The element E is fixed on the shaft B and its inner face abuts the surface A³. The casing ring C is also formed with a rectangular opening F which is in open communication with the bore D as illustrated, and two guide surfaces F¹—F¹ are formed on the inner walls thereof parallel to each other, which guide a cage or housing member G. 45 This housing member is substantially rectangular in its outer face, and is provided with a circular bore G¹ which is open at its lower end to provide space for the oil inlet port H and outlet port H¹, indicated in dot-

ted lines, and to permit the gear wheel E, to 55 mesh with the gear wheel E¹ which is fitted to rotate in contact with the bore G¹ in close relation with the wall thereof, and thereby dispense with a shaft, which reduces the cost of making the pump. Abutments I—I are 60 formed in the ring as shown, to limit the movement of the housing G and prevent the gear wheels E and E¹ from jamming, and the upward movement of the housing is also limited by the abutment J at a point where 65 the gears will still be in mesh but separated at the greatest predetermined distance.

The top of the ring C is provided with a stuffing box construction K, through which extends a stem L, having a thread L¹ to fit 70 the corresponding thread formed in the ring, and which is provided with a laterally extending circular flange L² which fits in a slot M formed in the housing and extending entirely across the same so that the housing 75 may be slipped into the ring C and engage the flange, after the stem has been first inserted in the chamber M and screwed upward to the position as shown, as will be readily understood. The handle N, is then 80 attached and by its use the housing may be raised and lowered within the abutments limits. An outer cap O, is provided with a plane surface P which serves as one side wall to provide the gear chambers, and is also provided with an extension O¹ in which is formed 85 a bore P¹ which is closed at its outer end and serves as an outer bearing for the shaft B. The inlet pipe is indicated by R and is connected to the boss R¹ in which is formed the 90 inlet passage H.

The parts are held together by bolts S—S. Assuming that the motor is running at a uniform 95 speed, to vary the amount of oil pumped per minute the handle N is turned to lift the housing to pump a less amount of oil and is lowered to pump a maximum supply. When the housing is raised and the gears thereby separated a greater distance apart, a portion 100 of the oil remains in the bottom of the gear between the teeth, since pockets are formed between the two adjacent teeth of one wheel and outer end of the adjacent gear, and these pockets are of greater capacity 105 when the gears are apart the extreme distance than when nearer to each other, and therefore the capacity of the pump may be changed while the pump is running, as will

be readily understood. By removing the cap O, all the parts may be removed from the casing C.

Having thus described my invention I claim as new:—

1. An oil pump comprising a casing having an inlet and outlet port for oil, a shaft, a gear wheel mounted on and driven by said shaft, a gear wheel in mesh with said first gear wheel and means for moving said last gear wheel to or from said first wheel to vary the volume of oil without changing the speed of the shaft, said means comprising a cage carrying said last gear wheel and having a laterally extending slot formed in its upper end and a stem having a flange at its lower end resting in said slot, said stem extending through said casing and serving to raise or lower said cage and hold it in its adjusted position.
2. An oil pump comprising a casing having an inlet and an outlet for fluid, and having a cylindrical chamber, and a rectangular shaped chamber formed therein, a gear wheel in said cylindrical chamber, a shaft for driving said wheel, a cage in said rectangular chamber, a gear wheel carried by said cage, said gear wheel being in mesh with said first wheel, means for moving said cage and for holding it in its adjusted position, and means for limiting the movement of said cage to prevent the wheels from interlocking, and from unmeshing.
3. An oil pump comprising a casing having an inlet and an outlet for fluid, and having a cylindrical chamber, and a rectangular shaped chamber formed therein, a gear wheel in said cylindrical chamber, a shaft for driving said wheel, a cage in said rectangular chamber, a gear wheel carried by said cage, said gear wheel being in mesh with said first wheel, means for moving said cage and for holding it in its adjusted position, and means for driving said wheel, a housing in said rectangular chamber, a gear wheel carried by said housing, said gear wheel being in mesh with said first wheel, means for moving said housing and for holding it in its adjusted position, and means for limiting the movement of said housing to prevent the wheels from interlocking, and from unmeshing, said pump construction embodying an end cap having a bore which serves as an inner bearing for said shaft; an outer cap plate; and an intermediate ring portion held therebetween and in contact therewith, which parts comprise the pump casing, and means for holding said parts together in separable relation.
4. An oil pump comprising a casing having an inlet and an outlet for a lubricant, a cylindrical and a communicating rectangular chamber formed within said casing, a gear wheel within the cylindrical chamber and a driving shaft for said gear wheel, a housing within the rectangular chamber and guided by the inner side walls thereof and a gear wheel carried by said housing for meshing relation with the first mentioned gear, a casing ring and an outer cap secured to the casing, an adjusting stem passing through the casing ring, said stem having means for connection with said housing whereby it may be moved with its gear wheel relative to the gear wheel in the cylindrical chamber to vary the volume of lubricant without changing the speed of the driven shaft.

In testimony whereof I affix my signature.

ALBERT E. GRANT.
